J. G. WALL,
BANK CHECK,
APPLICATION FILED SEPT. 2, 1914.

1,170,860.

Patented Feb. 8, 1916.

UNITED STATES PATENT OFFICE.

JUDSON G. WALL, OF NEW YORK, N. Y.

BANK-CHECK.

1,170,860.

Specification of Letters Patent.

Patented Feb. 8, 1916.

Application filed September 2, 1914. Serial No. 859,733.

To all whom it may concern:

Be it known that I, JUDSON G. WALL, a citizen of the United States, and resident of the borough of Brooklyn, county of Kings, city and State of New York, have invented certain new and useful Improvements in Bank-Checks, of which the following is a specification.

One of the important objects of this invention is to provide bank checks, drafts and other negotiable and non-negotiable evidences of debt, with a series of figures and symbols arranged in tabular form and adapted to be punched out or otherwise destroyed to indicate that the value represented by the instrument does not exceed the amount indicated by the punched-out or destroyed figures.

Another object of the invention is to provide a series of figures in tabular form which may be arranged at any convenient place on the face of the check or other instrument to be conveniently punched out or destroyed by an ordinary hand punch, or other simple device, whereby it may be simply and plainly indicated that the instrument does not exceed a certain value.

In the drawing, Figure 1 is a face view of a check with certain of the tabular figures punched out to indicate that the check does not exceed a certain value; Fig. 2 a detail view of the tabular arrangement of the figures, certain of the figures being punched out to indicate that the check does not exceed in value twenty-nine hundred dollars; and Fig. 3 a similar view, the figures being punched out to indicate that the check does not exceed a value of two hundred dollars; and Fig. 4 a similar view, the figures and marginal symbols being punched and cut out to indicate that the check does not exceed the value of one hundred dollars.

Referring to Fig. 1, the main body of the check, indicated by A is in the usual form and is adapted to contain the name of the payee, the amount of the check written in numerals and in words, and the signature of the drawer or maker. At any suitable and convenient place on the check I arrange a double column of figures as indicated at B, ten figures being arranged consecutively in each column and running from 1 to 9, with a cipher at the bottom of each column. These figures are arranged preferably in circles and the circles in one column are arranged with respect to those in the other column so

that the center of the circles of one column will be directly opposite the space or line between the circles of the other column. This double column of figures is preferably arranged parallel and close to one edge of the check. As shown in the drawing it is arranged close to the lower edge of the check. In the narrow space between the double column of figures and the edge of the check are arranged a series of stars or other symbols, the said stars being directly opposite the centers of the circles so that there will be twenty stars along the edge of the check directly in line with the centers of the twenty circles in the double column. At the top of the double column is arranged a space C in which there is a circle D containing two ciphers. Around the circle D are arranged nine figures, from 1 to 9 arranged in consecutive order. In the narrow space E containing the twenty stars or symbols F and directly opposite the center of the circle D is a star or symbol G. Adjacent the space C at the top of the column the words "Not over" appear. These words are preferably within the lines H which inclose the double column of figures. At the bottom of the series of figures is a space I which contains three ciphers and the word "Dollars." In the marginal space E opposite the "Dollars" space I is a star J. Around the edges of the check, close to the margin thereof, is placed a margin line K. This line is preferably heavy and distinct, and, of course, may be of a special color, if desired.

As shown in Fig. 1 the check is made out for twenty-nine thousand dollars. In order to indicate by means of the safety feature of the check that it is not for more than twenty-nine thousand dollars the numeral 2 in the left-hand column of figures is punched out and the star in the marginal space E corresponding to the said numeral 2 is also punched or cut out, thereby making a notch of considerable size in the edge of the check. The numeral 9 of the right-hand column of figures is also punched out and its corresponding star in the marginal space is punched or cut out to form another notch in the edge of the check. Thus punched the safety feature indicates that the check is for a value which does not exceed twenty-nine thousand dollars. The three ciphers in the space at the bottom of the column remaining unpunched indicate that the check is for one or more thousands of dol-

lars. When the numerals in the space at the top of the double column remain unpunched, and the ciphers in the circle D are punched or cut out, the check is for a thousand dollars or a multiple of a thousand. As illustrated in Fig. 1 the ciphers in the circle D are punched out, showing that the check is for an even thousand dollars, and thereby preventing the addition of hundreds of dollars to the check. It is to be noted that the notches in the edge of the check break the marginal line K, thereby making it necessary for a person raising the check to not only fill the notches, but to continue the marginal line across the filled-in portion. By providing the marginal line around the four sides of the check, the said line can not be cut off without materially altering the size and appearance of the check, thereby rendering detection easy. The purpose of cutting out the marginal edge of the check is that it is extremely difficult to patch such a cut. It is well known that persons skilled in altering checks sometimes fill or plug the holes in checks with paper pulp or similar material and that such plugging or filling is extremely difficult to detect. It is obviously very difficult, if not impossible, to successfully patch a notch in the edge of a check, for the reason that the filling or inserted material in the notch has an unattached or unsupported margin.

In Fig. 2 the punching indicates that the check does not exceed in value twenty-nine hundred dollars. It will be noted that the cipher in the left-hand column is punched, indicating that no values are to be shown in the column, and that the check is for an amount less than ten thousand dollars. The numeral 2 of the right-hand column is punched and the corresponding star or symbol in the marginal space is also punched or cut out; and in the space at the top of the column the numeral 9 is punched out.

In Fig. 3 the punching indicates that the check does not exceed two hundred dollars in value. In this punching the ciphers of both columns are punched indicating that no values show in said columns. The space at the bottom of the columns containing the word "Dollars" and the three ciphers is punched, and likewise the star in the marginal space E is cut out, indicating that the check is not of the value of one thousand dollars. In the space at the head of the column the numeral 2 is punched, thus indicating that the value of the check does not exceed two hundred dollars.

In Fig. 4 the punching and cutting indicates that the check does not exceed one hundred dollars in value. In this view the ciphers at the bottom of the double column are punched out, and their corresponding marginal symbols are cut out. The "dollars" space at the bottom of the column, is

punched and the marginal symbol therefore is notched out. This punching and cutting indicates that the check is for less than one thousand dollars. The numeral 1 on the space at the top of the column is punched out and the corresponding marginal symbol for this space is also notched out. This indicates that the check is for an amount less than one hundred dollars.

It is manifest that after the checks are cut and punched the numerals designating amounts above the value of the check may be destroyed by marking in any suitable manner; for instance, such numbers may be marked with a suitable ink-destroying acid, or acid-proof ink might be used for that purpose. This method of destroying the numbers above the amount of the check is illustrated in Fig. 1.

The notches in the edges of the check may be made by a suitable punch or by an ordinary pair of scissors, or in any other suitable manner.

With the arrangement of numerals shown checks running from one hundred dollars to ninety-nine thousand dollars may be efficiently protected against any material increase in the amount of the check. It is thought that the arrangement of numerals shown will be sufficient for ordinary commercial purposes, but, of course, if it be desired a third column of figures might be employed, and other changes might be made in the disposition and arrangement of the numerals to vary and expand the use of the system.

It is also manifest that while I have shown the protective device applied to ordinary bank checks it is capable of application to all negotiable and non-negotiable securities and evidences of debt. It may be applied to promissory notes, to stock certificates and the like.

The great advantage of a protective system of this character is that the punching may be made with a simple hand punch and at the same time the drawer of the check will be amply protected against loss by unlawful manipulation or raising of the value of the check.

Another great advantage of a check protective system of this character, is that it will not be necessary to use expensive protective paper for checks. It is well known that most checks are now printed on paper that is expensive to manufacture, but with this protective system, ordinary paper and medium-priced safety paper, will give ample protection against unlawful raising of the checks.

What I claim is:

1. A check, draft or other similar evidence of value having imprinted upon it a series of figures in two parallel adjacent columns said figures running consecutively

- from one to nine with a cipher in each column, one column of said figures indicating thousands and the other tens of thousands, these figures being adapted to be canceled to indicate that the number of thousands or tens of thousands in the face value of the check do not exceed the sum indicated by the canceled numerals, a symbol at the bottom of said columns and common to both which when canceled destroys the indicative value of the two columns of figures, another series of figures at the top of the columns running from one to nine inclusive any one of which when canceled indicates that the hundreds of dollars in the face value of the check do not exceed the sum indicated by the canceled numeral, and a symbol associated with said last series of figures which when canceled destroys the indicative value of said series of figures.
2. A check, draft or other similar evidence of value having imprinted upon it a series of figures in two parallel adjacent columns arranged near to and parallel with one edge of the check said figures running consecutively from one to nine with a cipher in each column, one column of said figures indicating thousands and the other tens of thousands, these figures being adapted to be canceled to indicate that the number of thousands or tens of thousands in the face value of the check do not exceed the sum indicated by the canceled numerals, a symbol at the bottom of said columns and common to both which when canceled destroys the indicative value of the two columns of figures, another series of figures at the top of the columns running from one to nine inclusive any one of which when canceled indicates that the hundreds of dollars in the face value of the check do not exceed the sum indicated by the canceled numeral, and a symbol associated with said last series of figures which when canceled destroys the indicative value of said series of figures, and a series of guide symbols arranged between said columns and the adjoining edge of the check and arranged respectively in line with the figures in the column, said symbols and the edge of the check being adapted to be punched out to correspond with the canceled numerals.
3. A bank check provided with a "not over" safety device, consisting of a pair of adjacent columns of figures running from one to nine and including a cipher, one of these columns representing thousands and the other tens of thousands, and a series of figures running from one to nine representing hundreds, this series of figures being arranged at one end of said column in a circular series, thereby inclosing a space which when punched or otherwise canceled will destroy the indicative value of all this latter series of figures.
4. A bank check provided with a "not over" safety device, consisting of a pair of adjacent columns of figures running from one to nine and including a cipher, one of these columns representing thousands and the other tens of thousands, and a series of figures running from one to nine representing hundreds, this series of figures being arranged at one end of said column in a circular series, thereby inclosing a space which when punched or otherwise canceled will destroy the indicative value of all this latter series of figures, said columns being arranged parallel to each other and near to and parallel with one edge of the check, the figures in one column being staggered with reference to the figures in the other column and both columns being located near one edge of the check, whereby any one of the figures in said columns may be canceled by notching the margin of the check and the aforesaid group of figures in its entirety may be canceled in a similar manner.
- In testimony whereof I hereunto affix my signature in the presence of two witnesses.

JUDSON G. WALL
